UNITED STATES PATENT OFFICE.

WILLIAM M. McNEIL, OF PORTLAND, INDIANA.

CISTERN-FORMING DEVICE.

SPECIFICATION forming part of Letters Patent No. 760,912, dated May 24, 1904.

Application filed September 21, 1903. Serial No. 173,991. (No model.)

To all whom it may concern:

Be it known that I, WILLIAM M. McNEIL, a citizen of the United States, residing in the city of Portland, in the county of Jay, and in the State of Indiana, have invented new and useful Improvements in Cistern-Forming Devices; and I hereby declare the following to be a full, clear, and exact description of the invention, such as will enable others skilled in the art to which it appertains to make and use the same.

My present invention relates to cistern-forming devices, or more particularly to a mechanism composed of coöperating and interdependent parts arranged and combined for the purpose of providing a form for molding cisterns or the like expeditiously and of a predetermined capacity.

The principal object in view is to provide a simple, durable, highly-efficient, and lightweight device for forming cement cisterns or the like in a minimum of time and with a maximum of accuracy.

Another object in view is the provision of an improved article of manufacture which may be made and sold at a comparatively low price, which will be easy of operation, may be readily assembled and disassembled, will be positive in action and accurate in the accomplishment of its intended results, and artistic and perfect in the completeness of its resultant formations.

A more specific object is to provide a device with which cisterns or the like may be formed of one or more heights providing ample and ready means for the support of the crown or roof of the construction being formed thereby and expeditious means for the removal of the device after the plastic compost construction has become somewhat hardened or set.

Other objects and special advantages of my invention will appear from the following specification and from the accompanying drawings, forming a part thereof.

My improvements herein set forth render the production of perfectly-formed cisterns or the like practical with a minimum of manual or mechanical energy, solving many of the most serious problems that have stood in the way of the practical attainment of that end.

My invention consists in a device of the class 50 set forth embodying certain new and useful features and details of construction and relative disposition of parts, substantially as hereinafter particularly set forth, illustrated in the drawings, and incorporated in the claims 55 hereunto appended.

The manner of carrying out my invention is clearly shown in the accompanying drawings, in which—

Figure 1 is a central vertical section of my 60 mechanism assembled, showing the interior and taken on the line Y Y of Fig. 2. Fig. 2 is a horizontal cross-section of same, taken on the irregular line X X of Fig. 1. Fig. 3 is a detail elevation of a portion of the center post 65 and the mechanism operative thereon. Fig. 4 is an isometrical inside view of two of the sections or stays slightly separated. Fig. 5 is a detail inside view of a portion of two sections, same being the two to be last positioned 70 in assembling the device; and Fig. 6 is a detail plan of the ends of two adjoining sections somewhat enlarged.

Similar indices refer to and denote like parts throughout the several views of the drawings. 75

My improvements herein shown and described are intended, primarily, for use in forming cement cisterns within the ground. However, it will be seen that at least some of the parts are applicable in connection with a tank-forming device, as specifically described and claimed in my application relating thereto filed simultaneously herewith and bearing same date thereof and serial number next thereto. 80

In the accompanying drawings my present 85 invention is shown in detail, in which the letter A denotes the earth inclosing the cistern. The cistern proper consists of the bottom B, the vertical wall C, the sloping top D, and the neck E. The sections complete are shown 90 most clearly in Fig. 4 and in being assembled are placed in pairs one above the other, as shown in Fig. 1, two sections thus placed forming a length equal to the height of the body of the cistern. All of the sections, both 95 upper and lower, are substantially identical, except the last two pairs to be positioned. The former are shown in Fig. 4 and consist

of an oblong slightly-curved metal plate 1. Along the edge of one of the sides of the plate 1 is a rib 2, and across the top and bottom are the cross-ribs 3, which latter each extends 5 from the rib 2 to near the opposite edge of the plate 1, as shown. Secured to the inner face central of the upper and lower ribs 3 parallel with the rib 2 is a brace 4, the center of which is deflected to touch the plate 1, where 10 it is permanently secured by a rivet or otherwise, the ends of the brace being secured to the upper and lower ribs 3 by rivets or bolts, as indicated. By the above it is seen that the rib 2 stiffens one edge of the plate 1, the ribs 15 3 the top and bottom edges, and the brace 4 the center thereof. By the arrangement shown a tongue is formed of the edge of the plate 1 opposite the rib 2, which tongue may overlap the plate of the adjoining section, or 20 a space may be formed between the rib 2 and the plate 1 to receive the tongue of the adjoining section.

Near the free end of each of the ribs 3 is a staple 5, securing loosely the elongated link 25 6, and near the opposite end of each rib 3 is a pivoted L-shaped dog 7, adapted to be revolved but not removed. When two sections are brought opposite to each other, as in Fig. 4, they may then be brought together, as in 30 Fig. 6. The dogs 7 are then turned to point toward the staples 5, and the links 6 of the opposite section are then placed over the shank of said dogs, and the dogs are then turned in the opposite direction, as in Fig. 6, which will 35 lock the two sections together in the manner shown in Figs. 1, 2, and 6.

Placed vertically through the ribs 3, near each end thereof, are apertures 8, by which the lower rib of the upper section may be 40 secured to the upper rib of the lower section by a pin or bolt 9, as in Fig. 1.

In practice a hole is first formed in the earth A to the proper depth and of proper circumference, which will be somewhat greater than 45 the outer circumference of the assembled device. A row of sections is then set up resting on the bottom of the excavation and arranged in circular form, as in Fig. 2, bringing the edges of opposite sections together and securing 50 them as described and as shown in Figs. 1, 2, and 6. In order to provide means for the disassembling of the device after its work has been accomplished, the adjoining edges of 55 two of the sections are somewhat modified to form the construction shown at one point in Fig. 2 and in detail in Fig. 5. In the ends of the ribs of one of said sections are permanent dowel-pins *a*, and in the case of the opposite modified section the ribs 3 are formed shorter 60 than in the preceding sections, with a horizontally-disposed bolt 10 projecting inward and having a threaded nut thereon.

The numeral 11 denotes an angle-iron of same width as the ribs 3, on which it contacts, 65 having a longitudinal slot *b* in its longer por-

tion, through which slot may pass the inner end of the bolt 10, with said nut on the bolt 10 adapted to secure said angle-iron at various points against the face of the rib 3, as shown in Fig. 5. Through the short portion of the angle-iron 11 is a hole adapted to receive said pin *a* of the opposite section. After all of the other sections are positioned the two modified sections are inserted with the metal portion 1 of the section having the angle-iron overlapping the metal portion of the opposite modified section, and the disparity between the two sections is then compensated for by moving the angle-iron 11 toward the opposite section, entering the pin *a* in said hole in the angle-iron, and then by tightening the nut of the bolt 10 the first or lower tier of sections are assembled in substantially the manner shown and described.

The upper tier of sections are of identical 85 construction and are assembled as the aforesaid lower sections, with the lower ends of the upper sections resting on the upper ends of the lower sections, and the two tiers of sections are connected and secured together by 90 the pins or bolts 9, as above set forth. After the said two tiers of sections have been assembled I then place the square center pole 12 vertically in position with its lower end resting on the bottom of the cistern or on the 95 earth at the bottom of the excavation with its upper end extending above the surface of the ground.

The numeral 13 represents a circular disk of an outside diameter the same as the interior diameter of the neck E of the cistern, with a central opening through said disk to allow the center pole to slide therethrough. Extending up from two opposite sides of opening in said disk are straps 14, formed, preferably, of strap-iron or other thin metal. Said straps are secured at their lower ends to said disk 13 and then extend upward along the side of the pole 12, with their upper ends bent outwardly at right angles to form handholds, and through said straps are oppositely-disposed holes to receive the securing-pin 15 thereacross, as shown in Fig. 1, and through the pole 12 are a series of holes, as indicated in Fig. 3, also to receive said pin 13 and by which 115 said disk may be secured at the desired point on the pole 12, as shown in Figs. 1 and 3.

The numeral 16 denotes a smaller disk below the disk 12, also slidably on the pole 12, and is adjustably connected to the disk 13 by the two connecting-irons 17, which latter are secured to the under side of the disk 13 and then extend down parallel with the pole 12 and pass through slots formed through the disk 16, and a series of holes are formed 125 through the lower portions of the irons 17, as shown in Fig. 3, whereby the disk 16 may be raised or lowered independent of the disk 13 and secured by inserting pins through said holes in the irons 17 below the disk 16. Rest- 130

ing on or secured to the periphery of the disk 16 and radiating outward and upward therefrom are a plurality of arms 18, having notched upper ends, as shown in Fig. 3.

5 The numeral 19 indicates a two-part ring having at two opposite points a hinge, as indicated in Fig. 2, whereby it may be folded together in order that it may be passed through the neck E of the cistern, said ring being 10 adapted to rest on the notched ends of the arms 18, as shown in Fig. 2.

After the device is assembled to the point above stated I arrange crown-sheets of any well-known construction with their outer ends 15 resting on the tops of said upper sections and with their inner ends engaged with or supported by the disk 13, which may be accomplished in a variety of ways, with their center portions resting on the ring 19, which 20 forms the principal support therefor. I then fill in the space between the earth A and the sections with a compost of plastic cement or the like and also place a like thickness of the same over the crown-sheets and then form 25 the neck E in any well-known manner. After the cement has sufficiently hardened I remove the pin 15, thus allowing the disks 13 and 16 to slide down the pole 12, carrying with them the ring 19, consequently removing the main 30 support for the crown-sheets, thus allowing them also to fall to the bottom of the cistern or to be easily removed singly. The said parts are then removed from the cistern and the sections are dissembled and also removed 35 one by one.

The bottom B may be formed either before or after the formation of the sides of the cistern, as desired.

In the accompanying drawings I have shown 40 the device to be only eight sections in circumference, simply as a matter of convenience, whereas in actual practice a greater number of sections will be employed ordinarily in order to attain the desired circumference and at the same time make the sections 45 handable.

From the above description, taken in connection with the accompanying drawings, it will be seen that I have produced an improved 50 cistern-forming mechanism embodying the objects otherwhere referred to in this specification and appearing in the accompanying drawings.

While I have illustrated and described the 55 best means now known to me for carrying out my invention, I wish it to be understood that I do not restrict myself to the exact details of construction shown and described, but hold that any slight changes or variations in such 60 details as would suggest themselves to the ordinary mechanic would clearly fall within the limits and scope of my invention.

Having now fully shown and described my 65 invention and the best means for its construction and operation to me known at this time,

what I claim, and desire to secure by Letters Patent of the United States, is—

1. A cistern-forming device consisting of an upper and a lower tier of separable sections temporarily connected to form a vertical 70 drum, a center post extending through and above the drum thus formed, a disk movable on said post, means for securing said disk to said post at different elevations, a second smaller disk below the first-named disk also 75 movable on said post, means for suspending the second disk from the first disk adjustably, arms extending upward and outward from the lower disk with shoulders formed in their upper ends, and a two-part hinged ring supported 80 by the shoulders of said arms, all substantially as shown and described and for the purposes set forth.

2. A cistern-forming device consisting of an upper and a lower tier of separable sections, 85 each of said sections consisting of an oblong plate, a rib secured along one of the sides and a rib secured across each of the ends of said plate leaving a tongue formed of the free edge of said plate, a brace extending between the 90 end ribs and secured in the center to the center of said plate, and means for securing together the sections thus formed, substantially as shown and described.

3. A cistern-forming device consisting of an 95 upper and a lower tier of separable sections, each of said sections consisting of a metal plate, a rib secured along one of the longer edges of the plate and forming a groove between it and the plate, a rib secured across 100 the top and one across the bottom edges of said plate and extending from the first-named rib to near the opposite edge of said plate, a 105 staple carrying an elongated link, said link loosely secured by said staple, said staple being secured near one end of said cross-ribs, an L-shaped revoluble dog mounted in the opposite portion of said cross-ribs with means whereby said link may be placed over the dog 110 of the opposite section and secured by turning the dog to lock the adjoining sections together, all substantially as shown and described.

4. A cistern-forming device consisting of a plurality of sections adapted to be set up forming a circle, the adjoining edges of the last two sections having means for varying the circumference of the assembled device, said means consisting of angle-irons having a longitudinal slot in their longer portions, a bolt 115 120 adjustably securing said angle-iron, and means for engaging and securing the outer end of the angle-iron to the opposite section, all substantially as shown and described.

5. A cistern-forming device consisting of an 125 upper and lower tier of separable sections, each of said sections formed of a curved plate, ribs secured across each end and along one of the sides of the sections, a brace extending between the end ribs and bent in and secured near the 130

center to the body of the section, means for securing the sections together to form a pair of circular drums with one drum resting on the other, a center post adapted to be placed through said drums vertically and to extend thereabove, a crown covering the top of the upper sections and resting thereon, means for supporting the crown in the center and for withdrawing its support when the cistern is

completed, all substantially as shown and described.

In testimony whereof I have hereunto signed my name to this specification in the presence of two subscribing witnesses.

WILLIAM M. McNEIL.
